UNITED STATES PATENT OFFICE.

LORENZO DOW, OF DENVER, COLORADO.

WIRE FENCE.

SPECIFICATION forming part of Letters Patent No. 247,893, dated October 4, 1881.

Application filed January 24, 1881. (No model.)

To all whom it may concern:

Be it known that I, LORENZO Dow, of Denver, Arapahoe county, and State of Colorado, have invented a new and useful Improvement 5 in Wire Fences, of which the following is a specification.

The invention consists in combining sheet-metal posts open longitudinally to give elasticity, and provided with tongues, with wire 10 rails, of which one is wrapped around each post, whereby the wires are kept taut, as hereinafter described.

In the accompanying drawings, Figure 1 represents a section of fence constructed with my 15 improved posts. Fig. 2 is an elevation, in larger size, of one of the posts with wires attached. Fig. 3 is a horizontal section of the post, and Fig. 4 represents a cross-section, showing a modification of the post.

Similar letters of reference indicate corresponding parts.

The posts A are formed from strips of sheet-iron rolled into the required tubular form, either 20 round, tubular, or otherwise. The posts are preferably formed tapering, the larger end being the base; and instead of being complete tubes the edges are left a short distance apart, so that 25 the post has a slot lengthwise, as shown at a in Fig. 3, and is rendered elastic. At the side 30 of the post opposite to slot a there are tongues or hooks c, formed by a V-shaped cut made in the metal while in flat form, and at the base of the tongue the metal is removed sufficiently to give space for the wires b. This construction 35 of hook is simple and convenient, as the wire

is retained in place, while being free to slip lengthwise. These posts are to be set directly into the ground, and where the soil is not too hard and stony can be driven. To facilitate driving the lower ends are formed beveling, so 40 that the solid side extends as a cutter, d. The posts may be galvanized or covered with asphaltum, and will thus be rendered practically indestructible.

In building fences with these posts the posts 45 are first set and the wires then strung by turning out the tongues c, putting the wires in place, and then bending the tongue back. On each post one of the wires is given a turn around the post, so that each wire, when four are used, is 50 thus attached to every fourth post, as illustrated in Fig. 1. The wires are thus put under tension, their contraction is allowed by the elasticity of the post, and any slack by expansion is taken up by the posts.

This post is inexpensive, light, and by its 55 shape has the greatest possible amount of strength in proportion to the material used.

Having thus described my invention, I claim as new and desire to secure by Letters Patent—

In wire fences, the tubular sheet-metal posts A, open longitudinally to give elasticity, and provided with tongues c, in combination with wire rails b, of which one is wrapped about each 65 post, as and for the purpose specified.

LORENZO DOW.
